UNITED STATES PATENT OFFICE.

CHARLES E. BENTLEY, OF NEW YORK, N. Y.

DESIGN FOR A PILLOW-TOP.

SPECIFICATION forming part of Design No. 35,593, dated January 21, 1902.

Application filed November 18, 1901. Serial No. 82,787. Term of patent 3½ years.

To all whom it may concern:

Be it known that I, CHARLES E. BENTLEY, a citizen of the United States of America, and a resident of the borough of Manhattan, city of New York, State of New York, have invented and produced a new and original Design for a Pillow-Top, of which the following is a specification, reference being had to the accompanying drawing, forming part thereof, and which is a plan view of a pillow-top illustrating my design.

This design comprises a centerpiece or field representing a number of blooming poppies 1, grouped in a circle or wreath, and a foliated marginal portion having the outline of a series of leaf-like tabs 2, which radiate from the poppy wreath and taper outward at the edges toward their point or outer end.

A minor feature of the design comprises a border or band 3, extending along the edge of each radial tab from its base to its point.

The more essential feature of the design is the central representation of a circular group or wreath of blooming poppies surrounded by radiating and tapering leaf-like tabs forming a foliated margin to the poppy wreath.

I claim as my invention—

The design for a pillow-top, substantially as herein shown and described.

CHARLES E. BENTLEY.
